UNITED STATES PATENT OFFICE.

WILLIAM L. KANN AND RALPH G. KANN, OF PITTSBURGH, PENNSYLVANIA.

GRADING AND SUPPLYING SYSTEM FOR ABRASIVES.

1,321,528.

Specification of Letters Patent. Patented Nov. 11, 1919.

Application filed February 23, 1918. Serial No. 218,624.

To all whom it may concern:

Be it known that we, WILLIAM L. KANN and RALPH G. KANN, both citizens of the United States, residing at Pittsburgh, Allegheny county, Pennsylvania, have invented a new and useful Improvement in Grading and Supplying Systems for Abrasives, of which the following is a full, clear, and exact description, reference being had to the accompanying drawings, forming part of this specification, in which—

Figure 1 is a plan view, largely diagrammatic, of apparatus embodying our invention.

Fig. 2 is a longitudinal vertical section of the grading apparatus, the plane of section on the line II—II of Fig. 3.

Fig. 3 is a plan view, of the apparatus shown in Fig. 2.

Figs. 4 and 5 are sections taken respectively on the lines IV—IV and V—V of Figs. 2 and 3; and

Fig. 6 is a fragmentary plan view showing a modified construction of grading box.

Our invention has relation to apparatus for use in grading and supplying sand, or other abrasive, or to grinding machines, such as plate glass grinding and smoothing machines.

The invention is designed to provide a grading and supplying system for abrasives, such as sand, by which the used abrasive coming from the grinding machines may be graded with a high degree of uniformity, and the successive grades collected for delivery back to the machines for further use as required. It is also designed to provide a system of this character which will be highly economical in its use of abrasive by

enabling the coarse abrasive delivered to the machine for any particular coarse grinding operation to be used up to a maximum extent during the subsequent finer grinding operations, thereby conserving all the useful particles of the abradant.

A still further object of the invention is to provide a system in which the abrasive too fine for further use, together with dirt and slimes, is effectively separated out, thereby getting the full benefit of the abradant at each step of the operation, and in which the several operations may be easily controlled as may be necessary to meet the various conditions which arise in practice.

A still further object is to provide a system in which the apparatus employed is simple

in its character and construction and not likely to get out of order; which can be installed and maintained at a relatively low cost, and which will not require the use of skilled labor.

In general, our invention provides a system of the described character, the use of which results in an increased output of superior product from the grinding machines in connection with which it is employed.

Our invention will be described as applied to apparatus for grading and supplying sand to plate glass grinding machines; but it will be understood that our invention is not limited thereto, and the term "sand" as used herein and in the appended claims is to be understood as including any other comminuted or granulated abradant which may be employed in systems of this character.

Referring to the accompanying drawings in which we have shown a preferred embodiment of our invention, the numeral 2 designates a plate glass grinding machine of any usual or suitable character, having the usual grinding runners 3, and which is surrounded by a ditch 4 into which the water and abrasive discharged from the machine is collected. 5 designates a new coarse sand supply, which may be of any suitable character, such as a sump or well of the character described and claimed in the co-pending application of William L. Kann, one of the present applicants, Serial No. 834,102, filed April 24, 1914. The new coarse sand delivered to this sump or well is washed therein and is delivered to the machine by a pipe 6.

7 designates a relatively shallow pit located at one side of the grinding machine and at a lower level than the table thereof. This pit is formed with two reversely inclined longitudinal gutters 7^a and 7^b, the gutter 7^a forming an outlet which may lead directly to a sewer (if the grade is such as to permit this) or which may discharge into a sump 8 from which the water, etc., may be removed in any suitable manner, forming no part of the invention. The gutter 7^b is inclined toward the receiving end of the pit 7, to a conduit 7^c which discharges into a well or sump 24 hereinafter described.

Placed in one end portion of the pit 7 is a used sand box or receptacle 9 into which the used sand and water from the grinding machine flows from the ditch 4 and conduit

10. 11 is a screen which is preferably employed where the conduit 10 discharges into said box 9 for the purpose of screening out any coarse foreign matter. The used sand box 9 is provided with an outlet at one end, controlled by an adjustable dam or weir 12, this outlet or overflow leading into a sluice-way 13 which conducts the sand and water to the series of grading boxes 14, 15, 16 and 17. These grading boxes are arranged in tandem, the overflow from one box passing into the next adjacent box, over the intermediate partitions 18 which are made independently adjustable as to height. Each of these boxes, is shown as having inclined side and bottom walls 21 converging toward a bottom outlet opening 22, arranged to discharge into the gutter 7^b of the pit 7, leading to the well or sump 24 which is underneath the used sand box 9. Each of the discharges 22 has a separate valve 23 by means of which it may be controlled. The used sand box is also provided with a valved bottom opening 25 discharging into the gutter 7^b. It is also provided with an adjustable overflow 26, at one side, arranged to discharge into the sewer connection 7^a. Each of the grading boxes 14, 15, 16 and 17 is also preferably provided with a valved outlet 27 located in one side of the box near its top, and arranged to discharge into said sewer connection 7^a. The opposite side of each of these boxes has a discharge opening controlled by a gate 27^a, and arranged to discharge into the gutter 7^b. 28 designates any suitable pump by means of which sand and water from the pit or sump 24 may be returned to the grinding table for reuse. 29 is an overflow leading from the upper portion of said pit or sump into the sewer connection 7^a and forming a means of holding constant head of water in pit or sump 24, by which means a practically constant volume of water is had for grading. 30 designates any suitable system of water pipes by means of which water may be introduced into the grading boxes 14, 15, 16 and 17. The last grading box 17 is provided with an adjustable overflow 31 leading into a box 32 having a discharge opening leading into the sewer connection 7^a and controlled by an adjustable gate 33.

The operation of the system is as follows: 55 New coarse washed sand is supplied to the table; the grinding machine is started and new sand is ground under the runners 3 and is thrown by centrifugal action into the table ditch 4. From this ditch it is conveyed into the used sand box 9. When this box becomes filled with sand and water it overflows into the sluice-way 13, and thence into and over the series of grading boxes. There is deposited in each box its proper 60 grade of sand by reason of the different

specific gravities of the sand. It is desirable to so regulate the supply of water to the system that there will be substantially constant volume of flow over the tops of the series of grading boxes so that the grading 70 action will be substantially uniform at all times to cause each box to receive a substantially uniform grade of the sand. The slimes and sand too fine for further use pass from the last box over the overflow 31 into 75 the box 30 and thence in the sewer connection. The horizontal water flow over the boxes may be largely regulated by means of the adjustable overflow at 12 and 26.

As soon as sufficient new coarse sand has 80 been applied to the machine to effect the coarse grinding operation, the supply of this sand is shut off. The valve controlling the discharge 25 from the used sand box 9 is then opened, and sand and water from this 85 box pass into the gutter 7^b and thence into the well or sump 24, from which it is pumped up and delivered back to the table through the pipe 34. After again passing under the runners it flows back into the used 90 sand box 9. This cycle of operation is continued until all of the sand coarse enough to deposit in the box 9 is used up and only practically clear water passes from the bottom discharge of said box and from the pit 95 24 onto the table. This substantially clear water serves for wash-out purposes. In the meanwhile, and during the course of this continuous cycle, the fine sands have been properly graded out and delivered in the 100 series of grading boxes 14, 15, 16 and 17. While the machine is being washed out, the valves of the discharges 27 from said boxes are preferably opened in order to allow surplus water to flow from the boxes into the 105 sewer connection. When the machine is washed out the bottom discharge valve 23 of the first grading box 14 is opened and fine sand from this box is allowed to flow into the gutter 7^b, and thence through conduit 7^c 110 to the sump or well 24; and is raised therefrom by the pump and delivered to the table. After the first box 14 has been emptied, the bottom discharge of the second box 15 is opened; and in this manner the successively 115 finer grade of the several boxes are delivered to the table in the proper sequence and substantially all the fine sands are used up and the grinding of the side of glass is completed.

Immediately before the first grade of fine sand from the box 14 is started in use, the overflow from the used sand box into the sluice-way 13 is closed by means of a gate 12, so that water and any contained slimes 125 too fine for use coming back from the table will be caused to overflow into the ditch 7^a, the bottom discharge valve 25 of the box 9 being also closed.

The pump which returns the sand from 130

the well or sump 24 to the machine is run at substantially constant speed (or pressure, if an air-lift pump is employed) in order to regulate the amount of water in the system 5 and keep it constant, the regulating means, of course, depending on the type of pump employed and the means of actuating the same. The overflow 29 from the upper portion of the well or sump 24 not only 10 causes the constant discharge of all useless slimes, etc., as conducted thereto, but also acts to maintain a constant head and pressure of water in the well. This is of particular importance where an air-lift pump 15 is employed.

It will be noted that each original batch of new coarse sand supplied to the machine is used up without waste during the operations of rough grinding and smoothing and 20 finishing, the supply of sand for the last named operations being furnished in proper quantity and in the required successively finer grades from the sand which has accumulated in the grading boxes during the 25 time that new fresh coarse sand is being supplied to the table, as well as during the time that the used sand from the box 9 is going to the table.

It will also be noted that in the described 30 operations, there is at no time any admixture of used sand with new coarse sand supplied to the table.

By the arrangement of grading boxes described whereby all of these boxes, together with the used sand box, is caused to 35 discharge into a single pit or sump 24, only one pump is required to deliver the successive grades of sand from such boxes to the table. The several overflows provide means 40 for freeing the system of slimes and sand too fine for further use, thus maintaining the sand which goes to the table in clean condition.

In some cases, it may be desirable to stop 45 the flow to the table of any particular grade of sand before all the sand of that grade has been removed from the pit 24. This can be readily accomplished by providing the pipe 34 with a valved branch 35 which 50 may have a flexible portion 36 therein. By closing the valve 37 in the pipe 34 beyond its branch, the sand raised by the pump may be delivered either into the used sand box through such branch or returned to the 55 proper grading box.

Should it be desired at any time to make grades of finer sands (for instance, for re-grinding) either from new coarse sand, or from used sand, without operating the using 60 apparatus, this can be readily done as follows:

The connection to the gutter 7^a through the box 32 and gate 33 is closed, and a gate 33^a provided at the opposite side of the box 32 65 and controlling an opening arranged to dis-

charge into the gutter 7^b, is opened. If regrading of a portion of the sand in the grading boxes is necessary, the gate 27^a of such box or boxes is also opened, and the material contained therein directed back 70 into the well or sump 24. The used sand box 9 is supplied with new coarse sand or with used sand, with the necessary water. By means of the flexible pipe connection 35 and valve 37, the sand from the well or 75 sump 24 may be returned to the used sand box, or to any one of the grading boxes. The waste slimes and excess water are disposed of through the overflows 29 and gutter 7^a. The grading in this operation is controlled by the constant head in the well or 80 sump 24 maintained by its overflows; by the substantially constant rate of discharge through the pump 28, and by the substantially constant volume of horizontal flow 85 over the grading boxes.

In Fig. 6 I have shown a construction of grading boxes in which one of the side walls 38 may be adjusted toward or away from each other to thereby vary the cross section 90 area of the box.

We desire it understood that our invention is not limited to the particular construction, arrangement or combination of parts herein shown and described; but that 95 various changes may be made therein within the spirit and scope of the appended claims, thus, the grading boxes may be of any suitable construction; the overflows may be differently arranged. The material to be 100 graded may be either a used abradant as herein specifically described, or it may be a new abrasive which it is desired to grade. Such abrasive may be supplied to the system in any suitable manner; for instance, 105 directly into the sump 24; and the graded material instead of being delivered immediately back to a using apparatus, may be placed in storage or removed for use at distant points, and various other changes may 110 be made. For some abrasives a liquid other than water may be used.

We claim:

1. In apparatus for grading and supplying sand, the combination of a used sand 115 receptacle, means for supplying used sand to said receptacle, a system of grading boxes at a lower level than the source of supply of used sand and arranged to receive the overflow of abrasive and water 120 from the used sand box, a well or sump, means whereby the abrasive may be separately discharged from the used sand box and from the several grading boxes into said well or sump, and means for returning 125 sand and water from said well or sump to a point of use; substantially as described.

2. In apparatus for grading and supplying sand, the combination of a used sand 130 receptacle, means for supplying used sand

to said receptacle, a system of grading boxes at a lower level than the source of supply of used sand and arranged to receive the overflow of abrasive and water from the used sand box, a well or sump, means whereby the abrasive may be separately discharged from the used sand box and from the several grading boxes into said well or sump, and means for returning the sand and water from said well or sump to a place of use or to the used sand box; substantially as described.

3. In apparatus for grading and supplying sand, the combination of a used sand receptacle, means for supplying used sand to said receptacle, a system of grading boxes at a lower level than the source of supply of used sand and arranged to receive the overflow of sand and water from the used sand box, said overflow being arranged to travel over the said boxes, a well or sump, means whereby the sand may be separately discharged from the used sand box and also from any one of the grading boxes into said sump, and means for raising sand and water from said sump and delivering it to a place of use, together with means for controlling the volume of flow over the grading boxes; substantially as described.

30 4. In apparatus for grading and supplying sand, the combination of a used sand receptacle, means for returning the used sand from a place of use to said receptacle, a system of grading boxes at a lower level than the source of supply of used sand and arranged to receive the overflow of abrasive and water from the used sand box, a sump, means whereby the abrasive may be separately discharged from the used sand box and from the several grading boxes into said sump, and means for returning sand and water from said sump to the place of use, together with means for varying the capacity of said boxes; substantially as described.

45 5. In apparatus for grading and supplying sand, the combination of a used sand receptacle, means for returning the sand from a place of use to said receptacle, a system of grading boxes at a lower level than the place of use and arranged to receive the overflow of sand and water from the used sand box, said overflow being arranged to travel over the said boxes, a well or sump, means whereby the sand may be separately discharged from the used sand box and also from any one of the grading boxes into said sump, and means for raising sand and water from said sump and delivering it to the place of use, together with means for controlling the volume of flow over the grading boxes, together with means for varying the height of overflow between successive boxes; substantially as described.

6. In a sand grading and supplying system, a pit, a used sand box in said pit, a conduit for conducting the used abrasive and water into the used sand box, a series of grading boxes in said pit connected to the used sand box and arranged to receive the overflow by gravity therefrom, a sump into which the used sand box and the grading boxes are arranged to discharge, and means for returning the sand from said sump to a place of use, said boxes also each having a controllable overflow, and a conduit arranged to receive the discharge from said overflows, substantially as described.

7. In a sand grading system, a pit located below the level of the source of sand supply, a series of grading boxes located in said pit, means for causing a gravity flow of the sand over said boxes, a sump connected with the pit, means whereby the contents of the several boxes may be successively discharged by gravity into the pit and thence into the sump, substantially as described.

8. In a sand grading system, a pit located below the level of the source of sand supply, a series of grading boxes located in said pit, means for causing a gravity flow of the sand over said boxes, a sump connected with the pit, and each of said boxes having a bottom discharge into the pit and thence to the sump, and another discharge at a higher level into said pit and sump, together with valve means for separately controlling said discharges, substantially as described.

9. In a system of the character described, a pit located below the level of the source of sand supply, said pit having a sump therein and also two gutters one leading into the sump and one leading therefrom, and a system of grading boxes having means for discharging their contents into either one of said gutters, together with an overflow receptacle at the end of the system of grading boxes, and means whereby said receptacle may be made to discharge into either of said gutters, substantially as described.

10. In a sand grading system, a pit having two bottom gutters, one leading to a waste outlet, a deep sump into which the other gutter discharges, and a series of grading boxes in said pit, each of said boxes having a waste overflow arranged to discharge into the first named gutter, and a bottom outlet, arranged to discharge into the second gutter, and a box into which the last grading box is arranged to overflow, said box having a controlled outlet to both gutters, substantially as described.

In testimony whereof we have hereunto set our hands.

W. L. KANN.
RALPH G. KANN.
